UNITED STATES PATENT OFFICE.

BERNE NADALL, OF CHICAGO, ILLINOIS, ASSIGNOR TO THE BARNHART BROS. & SPINDLER, OF SAME PLACE.

DESIGN FOR A FONT OF TYPE ORNAMENTS.

SPECIFICATION forming part of Design No. 25,740, dated June 30, 1896.

Application filed April 13, 1896. Serial No. 587,412. Term of patent 7 years.

To all whom it may concern:

Be it known that I, BERNE NADALL, a citizen of the United States, residing at Chicago, county of Cook, and State of Illinois, have 5 invented and produced a new and original Design for a Font of Type Ornaments, which is fully set forth in the following specification, reference being had to the accompanying drawing, forming a part thereof.

10 This design comprises twenty-six ornaments adapted to be combined especially for the formation of borders. A few of the desirable combinations are illustrated in the drawing inclosing the group of ornaments in 15 heterogeneous order.

15 The general character of the design is that of conventional imitation of carvings after coralline, scroll, and leaf forms, the lines being mainly light, but not hair-lines. More 20 expanded portions of the scroll or carving imitations are joined by the light lines in a manner to produce the appearance of being shot through by light double-line curves of long radius, as in forms 16, 20, 21, and 23, or

of being appended to or developed from such 25 light double-line curves, as stems, as in Nos. 8, 9, 10, 12, 13, 14, 15, 17, 18, 19, 22, 24, 25, and 26, and certain forms are adapted to serve as such stems and to be appended for that purpose to any other form in composition, as 30 No. 11. Forms 1 2 3 4 5 6 7, being devoid of stem-lines, are adapted for combination with stem-forms or forms having stem-lines in any desired order. The long double-line curves of large radius, which constitute the stems of 35 many forms, as well as the forms made up of such double-line curves alone, are adapted for combination to produce a vine-like appearance, upon which, and in association with which, the more expanded portions of the de- 40 sign appear as conventional foliage.

I claim—

The design for a font of type ornaments herein shown and described.

BERNE NADALL.
